UNITED STATES PATENT OFFICE.

NEWTON S. HILLYARD, OF ST. JOSEPH, MISSOURI.

DUST MOP.

Application filed December 3, 1926. Serial No. 152,364.

My invention relates to mops and more particularly to mop swabs adapted for attachment to mop heads that are provided with means of receiving and distributing a liquid for the treatment of floors.

The purpose of my invention is to provide a mop swab element and a mop head element which in combination produce an implement convenient in assembly and use, efficient in service both as a dusting mop and as a distributor of a liquid and having a minimum of parts. I particularly have sought to provide and have so provided an arrangement of mop swab and head whereby the under parts of the head are completely covered by the swab so that danger of marring the floor by accidental contact of metal parts is obviated.

In accomplishing my purpose I provide as an element of the mop head, an elongated shallow pan in which the adjustable head of a mop handle is positioned; a mop swab element constructed on two pouches or mittens of duck or like fabric designed to be drawn over the laterally extending parts of the pan, straps having grommets for engagement with a projecting screw provided in the handle head, and a wing nut on the screw to establish the engagement of the grommeted straps with the handle head to hold the paired elements of the mop swab on the mop head pan. Openings in the upper sides of the pouches are provided through which the liquid may be poured into the pan.

My arrangement and construction and the particular advantages thereof will be more particularly and explicitly detailed in the description in which reference will be made to the accompanying drawings in which:

Fig. 1 is a perspective view of a mop, the parts being in functioning position.

Fig. 2 is a longitudinal section through the center of the mop.

Fig. 3 is a perspective view of the mop, showing one of the swab members removed.

Fig. 4 is a cross sectional view on the line 4-4 of Fig. 3.

Fig. 5 is a cross sectional view of the handle and head on the line 5-5 of Fig. 3.

Referring more in detail to the drawings:

1 designates the pan element of a mop head, the pan having the longer sides 2 provided with openings 3. A mop handle 4 is secured to the pan 1 by the agency of a block 5 riveted thereto and receiving the end 6 of the handle, the block and the handle being

kept in engagement, which engagement may be adjustable, by means of a screw 7, a nut 8 locking the handle and block together, the screw 7 projecting substantially beyond the extent necessary for the service so far detailed and for a purpose later to be described; a wing nut 9 being positioned on such extended portion of the screw.

The swab element constitutes an important feature of my present invention. It will be observed that the pan element of the head, and the means of attachment to a handle, are similar to the same elements in my application, Serial No. 41,426. I am providing herewith, however, substantial variations in the construction of the mop swab and means of attaching the swab to the mop head as distinguished from my invention referred to, and constituting improvements thereon.

I provide paired mop swab pouches or mittens designated 10 and consisting of the mop fabric or cords 11 which as illustrated consists of tufts secured to the cloth bases of a pouch designated 12 and which might be described as the palm of the mitten, considering the swab mittens held by the hands constituted of the mop pan for passing back and forth over the floor to be treated by the mop, the back of a mitten or the upper enclosure of a pouch designated by 13 having a central vertical opening 14 suitably reinforced as at 15. The back of a mitten has a cutaway portion indicated at 16 whereby the mitten is fitted to the handle block. A strap 17 is suitably secured to the back of a mitten and is provided with a grommet 18 in its free end for fastening the mitten to the handle block.

In assembling the device the two pouches are drawn over the ends of the pan, the cutaway portion 16 of the pouches providing for fitting of the upper sides of the pouches around the handle block head and the close contact of the meeting edges of the mop swab mittens so that the depending fabric will offer a surface of unity, a condition idealized in the depending fringe as shown in Figs. 1 and 2. The straps 17 are adapted by length to lap when the pouches are joined for extending the grommets over the screw 7; the wing nut 9 being twirled on the screw and pressing the grommets and so enabling the straps to hold the pouches of the mop swab in position on the pan.

The service of the opening 14 in the back

of a mitten lies in the reception therethrough of the liquid intended for dispersion through the mop fabric. The liquid as admitted is received by the pan; is then let out through the side openings 3 provided in the longer sides of the pan and so emerges into the lower parts of the pouches, and percolates through their substance to the fringe-like mop fabric 11.

16 What I claim and desire to secure by Letters Patent is:

1. A mop comprising a liquid distributing pan, a handle attached to the pan and a swab member enclosing the pan and comprising 15 paired pouches having openings for admission of liquid, mop fabric attached to said pouches and straps secured to said pouches and securing the swab element to the handle.

2. A mop comprising a liquid receiving pan having outflow openings, a handle engaged with the pan and a swab element including paired pouches to enclose said pan, and means of securing the pouches on the pan.

25 3. A mop comprising a liquid receiving pan having outflow openings and a handle secured to said pan adjacent its central portion, and a swab element comprising paired pouches, the pouches having openings in their upper sides, a mop fabric secured to said pouches, a stud on the handle, straps provided with grommets engageable with the stud, and means whereby the pouches are secured together and to the pan.

35 4. A mop comprising a liquid receiving pan having outflow openings in its vertical sides and a handle centrally seated in said pan

and secured thereto, and a swab element comprising paired pouches with mouths laterally opposed for reception of the pan 40 and upper lips cut away and having openings in the upper walls adjacent said cut away lips, the openings and the lips being reinforced with stitching, and straps secured to said pouches and having free ends, and 45 means removably securing the straps to the handle.

5. A mop comprising a rectangular cupped perforate head constituting a distributor, a handle attached to the head and swab 50 elements including paired pouches to receive the ends of the head and means for securing the pouches on the head.

6. A mop comprising a head, a handle, 55 means for securing the handle to the head, paired swab elements for receiving the ends of the head, and straps on the swab elements having means to engage the swab elements with the handle securing means.

7. A mop comprising a head, a stud carried 60 by the head, swab elements including paired pouches for receiving the ends of the head, and straps secured to the pouches and engageable with the stud for securing the pouches on the head.

65 8. A mop comprising a head, a threaded stud carried by the head, swab elements comprising paired pouches for covering the head, straps secured to the pouches, openings in the ends of the straps to be received by the stud, and a nut threaded on the stud to retain the straps.

In testimony whereof I affix my signature.
NEWTON S. HILLYARD.
